(57) **CLAIM**

The ornamental design for a controller for endoscope, as shown and described.

DESCRIPTION

FIG. 1 is a top, front and right side perspective view of a controller for endoscope showing my new design; FIG. 2 is a front elevational view thereof; FIG. 3 is a rear elevational view thereof; FIG. 4 is a top plan view thereof; FIG. 5 is a bottom plan view thereof; FIG. 6 is a left side elevational view thereof; FIG. 7 is a right side elevational view thereof; and, FIG. 8 is a top, front and right side perspective view thereof in a manner of use.

The broken line portions of the controller for endoscope throughout the drawings are shown to illustrate environment only and form no part of the claimed design.
